Primary Examiner — Jennifer Rivard
Assistant Examiner — April Rivas

(57) **CLAIM**

The ornamental design for a luggage with integrated trolley, substantially as shown and described.

DESCRIPTION

FIG. 1 is a perspective view of a piece of luggage with an integrated trolley, with the trolley extended, showing my new design;

FIG. 2 is a top view thereof;

FIG. 3 is another perspective view thereof;

FIG. 4 is a back view thereof;

FIG. 5 is a left side view thereof;

FIG. 6 is a front view thereof;

FIG. 7 is a bottom view thereof;

FIG. 8 is perspective view of the piece of luggage with the integrated trolley, with the trolley collapsed;

FIG. 9 is a top view thereof;

FIG. 10 is another perspective view thereof;

FIG. 11 is a front view thereof;

FIG. 12 is a left side view thereof;

FIG. 13 is a back view thereof; and,

FIG. 14 is a bottom view thereof.

The broken lines illustrate portions of the luggage with integrated trolley and form no part of the claimed design.

1 Claim, 14 Drawing Sheets
